TALMA T. GREENWOOD, OF EAST TEMPLETON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH AND CONTACT STRUCTURE

Application filed June 29, 1929. Serial No. 374,837.

This invention relates to high potential electric switches and has for an object the provision of means to improve the contact pressure between the separable switch members, particularly when they are traversed by a heavy current.

It has been found that when plane contact faces are employed for the cooperating members of an electric switch, at best only a point to point contact is obtained. Consequently, the use of contact members presenting spheroidally formed confronting contact faces is advantageous, since the heat is more readily absorbed and dissipated from the contact surfaces and vaporization of the metal thereof is diminished. Current flowing through the conducting paths of the switch members is largely concentrated at the surfaces thereof, and consequently where the current is concentrated at the center or tips of the contact members the U-shaped current path thus present sets up a strong repulsive force which acts against the contact members in a direction to force them apart and draw an arc therebetween.

It is an object of this invention to provide means to overcome this repulsive force set up by the natural current path through the contacts and further to enhance the contact pressure therebetween.

Another object is the provision of a contact supporting solenoid having resilient convolutions which support one of the contact members, the convolutions being attracted toward each other when heavy current flows through them, whereby to press the contact member forcibly against the cooperating contact member.

A further object of the invention is the provision of means effective upon the tripping of the switch to accelerate the initial opening movement of the movable switch member.

A still further object is generally to improve the construction and operation of electric switches.

Fig. 1 is an elevation, partly in section, of the current conducting members of an electric switch embodying the invention.

Fig. 2 is an enlarged sectional elevation of

one of the relatively fixed contact members of Fig. 1.

Fig. 3 is a detail view showing diagrammatically the current path through a pair of cooperating contact members, the repulsive tendency of which is overcome by the present invention.

As herein shown, the invention is incorporated in a down break electric switch having stationary switch members including the fixed conducting studs 10 which are enclosed in insulating bushings 12 and stationary contact members 14 fixed to the lower ends of said studs and provided with lower contact faces 16 which comprise the fixed main contact members of the switch. Said main contact members 14 are further provided with integral outstanding brackets 18 which are adapted to support the fixed auxiliary contact members hereinafter to be described.

The movable switch member includes a laminated, or brush, member 20 having upwardly directed toe-sections 22 which engage the contact faces 16 and a vertically reciprocable insulating switch rod 24 which is adapted to be connected with suitable operating mechanism (not shown) for opening and closing the switch in the usual manner. Said movable switch member is further provided with a rigid horizontal bridging member 26 which is adapted to carry removably at its ends the upstanding auxiliary movable contact members 28.

In accordance with the present invention, the cooperating relatively fixed arcing contact members 30 are adapted to be supported yieldingly on said outstanding brackets 18. To this end, said contact members 30 as herein shown are provided with upwardly extended conducting shank portions 32 which are disposed alongside and in the same vertical plane with the switch studs 10. Said shank portions 32 are screw threaded at their upper and lower ends whereby to carry the contact members 30 removably at the lower ends thereof. The upper screw threaded ends of said shank portions 32 are received in threaded apertures 36 at the upper ends of upstanding cylinders 38 which are carried removably by said outstanding brackets 18 and up-

standing thereabove. The side walls of said cylinders are provided with a continuous spirally formed slot or kerf extending substantially throughout their lengths whereby to provide a helical resilient support for said contact members 30 as well as an electrically conducting solenoid in series therewith. A sleeve 42 of insulating material is disposed about said conducting shank portions 32 in the vicinity of the brackets 18, whereby to prevent contact between said brackets 18 and said shank portions. A lock nut 43 is provided at the extreme upper threaded end of said shank portions whereby to secure them fixedly at their upper ends in cylinders 38.

The cooperating arcing tips 28 and 30 are relatively massive whereby more readily to absorb and dissipate the heat generated at the contact faces when an arc is drawn therebetween. It has been found that spherical contacts, or contacts having spheroidally-formed confronting contact faces which present a single point contact, are particularly advantageous in this respect. However, the current path through a pair of such contacts, as indicated diagrammatically in Fig. 3, sets up a strong repulsive force due to the U-shaped current path in the vicinity of the contact tips, as indicated at 44, which tends to force the contact members apart and cause a destructive arc to form therebetween.

By the provision of the present invention, current passing through a switch stud 10 before passing through the auxiliary contacts 30 is obliged to traverse the helical turns of the cylinder 38 which is disposed about the shank portion 32 of the contact member and consequently sets up a magnetic reaction between the convolutions thereof which tends to contract the convolutions of cylinder 38 and consequently to urge the relatively fixed arcing member 30 downwardly into engagement with its cooperating contact member 28. It will be evident that the more current passed through the switch, the greater will be the force exerted against the contact member 28, which is held against downward movement by a latch or other suitable device associated with the switch operating mechanism, not shown. The shank portion 32 may be formed of magnetizable material if desired whereby to enhance the magnetic field and enhance the solenoid action of the convolutions of the cylinders 38.

A further advantage of this construction results, particularly when the switch is opened on heavy overload, in the initial acceleration imparted to the movable switch member by the solenoid action of the fixed arcing contact members. It will be obvious that this force operates to accelerate the movable switch member before the separation of the arcing contact members takes place so that a rapid movement of the switch member

is attained prior to drawing the arc between the auxiliary contact members.

It can be stated that the repulsive effect due to the current is present in any two engaged contact members, regardless of their configuration, so far as I am now aware. 70

It is old to use two mutually-attracted, unyielding contact supporting solenoids to hold the contacts engaged, but in such case one solenoid, alone, is without effect. Care must be taken in the design of such solenoids, otherwise the attractive effect between them will hold the switch closed, regardless of efforts to open it. This cannot be the case with the present invention. 75

The magnetic field of the solenoid is present in the arc zone of the auxiliary contact members so that the arc is caused to rotate about the contact members and thus to be the more rapidly extinguished. 80

The broad idea of utilizing a solenoid to rotate the circuit-interrupting arc is disclosed and claimed in my copending application Serial No. 755,353, filed December 11, 1924. 85

Various modifications may be made in the construction and arrangement of the parts without departing from the scope of the invention. 90

I claim:

1. An electric switch including the combination of a fixed current conducting stud terminated in a main contact block, a resilient solenoid having one end fixed to and electrically connected with said block and its other end free, an auxiliary contact member carried by the free end of said solenoid and disposed below said main contact block, a second and relatively unyieldingly supported auxiliary contact member adapted to be moved into engagement with the contact member of said solenoid whereby to include said solenoid in the electric circuit including said auxiliary contact members, said solenoid adapted when traversed by heavy currents to flex in a direction toward said second auxiliary contact member and urge said auxiliary contact members into engagement by reason of the magnetic reactions set up by the current traversing the turns thereof. 105 110 115

2. An electric switch including a relatively rigidly supported contact, a resilient solenoid having one end fixed and its other end free, and a second contact member carried by said free end, said solenoid arranged to be included in the circuit through the switch and, due to the current traversing it, to move the contact member carried by the free end thereof toward said other contact member. 120

3. An electric switch including separable main current carrying contact members, separable auxiliary arcing members, a resilient solenoid in series with said arcing members, and means whereby the solenoid contracts and exerts a force on one of said arcing mem- 125 130

bers to urge it in a direction toward and against the other when traversed by the switch current.

4. An electric switch including a contact, a resilient solenoid having one end fixed and its other end free, and a second contact member carried by said free end and extended through said solenoid, said solenoid arranged to be included in series with said contact member whereby to be influenced by the current traversing the circuit to flex axially and move its contact member into pressure engagement with said other and cooperating contact member.

5. An electric switch including a contact, a resilient solenoid having one end fixed and its other end free and a second contact member carried by the free end of and extended through and insulated from the convolutions of said solenoid, said solenoid arranged to be included in series with the circuit through the switch whereby to be influenced by the current traversing the circuit to alter its effective length and move the contact member carried by its free end into engagement with said other and cooperating contact member.

6. An electric switch including the combination of a depending current conducting stud terminated in a main contact block, a resilient solenoid having one end fixed to and electrically connected with said block and having its other end free for axial movement in a direction parallel to the length of said stud, an auxiliary contact member carried by the free end of said solenoid, a cooperating relatively rigidly supported contact member adapted to be moved upwardly into a definite circuit closing position in engagement with said first contact member, the convolutions of said solenoid being included in series with said auxiliary contact members and adapted to be traversed by the current through the switch and to be influenced thereby to effect an axial movement of its contact member into engagement with its cooperating contact member.

7. An electric switch including the combination of a fixed current conducting stud terminated in a main contact block having an outstanding bracket, a resilient solenoid having one end electrically connected with said bracket and extended thereabove alongside said stud, a contact member electrically connected with the free end of said solenoid and extended downwardly through the convolutions and insulated from the convolutions of said solenoid and also from said bracket, whereby to provide a current path between said main contact block and said auxiliary contact member which includes the convolutions of said solenoid, a cooperating contact member movable upwardly into a definite circuit closing position wherein it is in engagement with the contact member of said solenoid whereby to flex and expand said

solenoid axially, said solenoid arranged when traversed by an electric current to contract axially whereby to urge said contact members in a direction to exert a pressure therebetween.

8. An electric switch including the combination of a fixed conducting stud terminated in a main contact block, a resilient solenoid having one end fixed to and electrically connected with said block and its other end free, a pair of relatively separable auxiliary contact members one of which is rigidly supported and the other of which is carried by the free end of said solenoid, said auxiliary contact members having confronting spheroidally formed contact faces, means including the convolutions of said solenoid to overcome the repulsive force resulting from the normal current path through said contact members to exert an opposing force on the contact member carried thereby to urge it against the other and rigidly supported contact member.

9. An electric switch including the combination of a pair of cooperating contact members having confronting spheroidally formed contact faces, one of which contact members is rigidly supported, and means including a resilient solenoid which constitutes a support for the other contact member included in series with said contact members and arranged to be deformed by the magnetic reaction of the current passing therethrough to exert a force on the contact member carried thereby urging it into engagement with said other and rigidly supported contact member.

10. An electric switch including a current-contractible solenoid having a fixed end and a movable end, a contact member carried by said movable end, and a second contact member cooperating therewith, said solenoid being included in series with said contact member and arranged to contract by the current traversing it to urge its contact member against the other contact member.

11. An electric switch including a current-contractible solenoid having a fixed end and a movable end, a contact member carried by said movable end, and a second contact member cooperating therewith, said solenoid being included in series with said contact member and arranged to contract by the current traversing it to urge its contact member against the other contact member, said solenoid also constituting means to rotate the circuit-interrupting arc between said separated contact members.

12. An electric switch having separable contact members, and a solenoid in series therewith providing a support for one of them having spaced yielding convolutions and adapted to be contracted axially to urge its contact member against the other contact member when traversed by the switch current.

13. An electric switch having separable contact members, and a solenoid in series therewith providing a support for one of them, having spaced yielding convolutions and adapted to be contracted axially to urge its contact member against the other contact member when traversed by the switch current, said solenoid also constituting means to rotate the circuit-interrupting arc between said separated contact members. 70
14. An electric switch having separable contact members, a solenoid having yielding convolutions in series therewith and a fixed end and a free end which is attracted toward said fixed end by the current traversing the convolutions, and means connecting one of said contact members with said free end so that said contact members will be urged against each other by the contraction of the solenoid. 75
15. An electric switch having separable contact members, a solenoid having yielding convolutions in series therewith and a fixed end and a free end which is attracted toward said fixed end by the current traversing the convolutions, and means connecting one of said contact members with said free end so that said contact member will be urged against each other by the contraction of the solenoid, said solenoid also constituting means to rotate the circuit-interrupting arc between the separated contact members. 80
16. An electric switch having separable contact members, a solenoid in series therewith having spaced convolutions which are free to be attracted toward each other and to contract the solenoid by the current traversing them, supporting means for one end of the solenoid, and means connecting a contact member with the other end of said solenoid by which such contact member is urged against said other contact member by the contraction of said solenoid. 85
17. An electric switch having cooperating fixed and movable contact members, a solenoid located thereabove having a fixed lower end and a movable upper end and connected in series with said contact members and having spaced convolutions which are attracted toward each other by the current traversing the solenoid, thereby to move the upper end thereof downwardly, and means connecting one of said contact members with said upper end arranged to press said contact members together by the contraction of said solenoid. 90
18. An electric switch having cooperating fixed and movable contact members, a solenoid located thereabove having a fixed lower end and a movable upper end and connected in series with said contact members and having spaced convolutions which are attracted toward each other by the current traversing the solenoid, thereby to move the upper end thereof downwardly, and means connecting one of said contact members with said upper end per end arranged to press said contact members together by the contraction of said solenoid, said means including a rigid conducting rod which passes upwardly within said solenoid. 95
19. An electric switch having cooperating fixed and movable contact members, a solenoid located thereabove having a fixed lower end and a movable upper end and connected in series with said contact members and having spaced convolutions which are attracted toward each other by the current traversing the solenoid, thereby to move the upper end thereof downwardly, and means connecting one of said contact members with said upper end, arranged to press said contact members together by the contraction of said solenoid, said means including a rigid conducting rod which passes upwardly within said solenoid, and is composed of magnetizable material. 100
20. An electric switch having cooperating fixed and movable contact members, a solenoid located thereabove having a fixed lower end and a movable upper end and connected in series with said contact members and having spaced convolutions which are attracted toward each other by the current traversing the solenoid, thereby to move the upper end thereof downwardly, and means connecting one of said contact members with said upper end arranged to press said contact members together by the contraction of said solenoid, said solenoid also constituting a resilient support for its contact member. 105
21. An electric switch having cooperating fixed and movable contact members, a solenoid located thereabove having a fixed lower end and a movable upper end and connected in series with said contact members and having spaced convolutions which are attracted toward each other by the current traversing the solenoid, thereby to move the upper end thereof downwardly, and means connecting one of said contact members with said upper end arranged to press said contact members together by the contraction of said solenoid, said solenoid also constituting a resilient support for its contact member and also means to rotate the circuit-interrupting arc between said contact members. 110
22. An electric switch having a support, a resilient solenoid having axially-spaced convolutions fixed at its lower end to said support and having an upper end which is free to move toward said fixed end by the attractive effect of the current traversing the convolutions, a stud connected mechanically and also electrically with said free end and extended downwardly therein, a contact member carried by the lower end of said stud, and a movable contact member disposed below and cooperating with said fixed contact member. 115
23. An electric switch having a fixed contact member, a relatively rigidly supported movable contact member cooperating there. 120
- 16 17 18 19 20 21 22 23

with and movable into a definite switch closed position, and a spiral compression spring yieldably supporting said fixed contact member, whereby it can move while engaged by said movable contact member, said spring being electrically in series with said contact members and including means to urge its contact member into engagement with said cooperating contact member when traversed by the switch current.

24. An electric switch having separable contact members, a support of magnetizable material for one of said contact members, and means to magnetize said support including a solenoid which also provides a yielding support for said contact support.

25. An electric switch having separable contact members, a support of magnetizable material for one of said contact members, and means to magnetize said support by the current traversing said contact members including a solenoid which also provides a yielding support for said contact support.

26. An electric switch including separable contact members having engageable contact faces, a magnetizable support for one of said contact members extended thereinto and terminated adjacent the contact face thereof, and means to magnetize said support including a resilient solenoid which is fixed at one end and carries said magnetizable support at its free end.

27. An electric switch including separable contact members having engageable contact faces, a magnetizable support for one of said contact members extended thereinto and terminated adjacent the contact face thereof, and means to magnetize said support including a winding which surrounds said support and is connected electrically in series therewith.

28. An electric switch including the combination of a pair of cooperating contact members, and means included electrically in series with said contact members and constituting a support for one of them which acts to urge its contact member by electromagnetic forces due to current traversing the switch into engagement with its cooperating contact member and which also acts to set up a magnetic field which acts radially of the line of separation of said contact members whereby to rotate the circuit interrupting arc drawn therebetween.

29. In testimony whereof, I have signed my name to this specification.

TALMA T. GREENWOOD.
